Primary Examiner — Michelle E. Wilson*Assistant Examiner* — Clesce Moore, Jr.*(74) Attorney, Agent, or Firm* — ScienBiziP, P.C.(57) **CLAIM**

The ornamental design for a video phone, as shown and described.

DESCRIPTION

FIG. 1 is a front elevational view of a video phone showing our design.

FIG. 2 is a rear elevational view thereof.

FIG. 3 is a left side elevational view thereof.

FIG. 4 is a right side elevational view thereof.

FIG. 5 is a top plan view thereof; and,

FIG. 6 is a bottom plan view thereof.

The broken lines shown illustrate portions of the video phone that form no part of the claimed design.

1 Claim, 6 Drawing Sheets(56)
